(57) **CLAIM**

The ornamental design for an electronic expansion valve, as shown and described.

DESCRIPTION

FIG. 1 is a front elevation view of an electronic expansion valve showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a perspective view thereof.

The broken lines shown in the figures are included for the purpose of illustrating portions of the electronic expansion valve and form no part of the claimed design.
